(57) **CLAIM**

I claim the ornamental design of a square lid with vent for food container, as shown and described.

DESCRIPTION

FIG. 1 is a top plan view of a square lid with vent for food container showing my new design;

FIG. 2 is a bottom plan view thereof;

FIG. 3 is a right side elevation view thereof;

FIG. 4 is a left side elevation view thereof;

FIG. 5 is a rear elevation view thereof;

FIG. 6 is a front elevation view thereof; and,

FIG. 7 is a top, front perspective view thereof.

The broken lines shown in the figures depict portions of the square lid with vent for food container that forms no part of the claimed design.

1 Claim, 7 Drawing Sheets
